CLAIM

The ornamental design for a pole mounting system for
lockable key housing, as shown and described.

DESCRIPTION

FIG. 1 is a front perspective view showing my new design;
FIG. 2 is a rear perspective thereof;

FIG. 3 is a rear perspective view thereof;

FIG. 4 is a partial front perspective view thereof;

FIG. 5 is a top view thereof;

FIG. 6 is a front view thereof;

FIG. 7 is a bottom view thereof;

FIG. 8 is a rear view thereof;

FIG. 9 is a left side view thereof;

FIG. 10 is a right side view thereof;

FIG. 11 is an environmental view thereof; and,

FIG. 12 is an environmental view thereof.

Portions shown in broken line are for illustrative purposes
only and form no part of the claimed design.
